INVENTOR.

BY Viggo LAURSEN
Martin E. Anderson

UNITED STATES PATENT OFFICE

124,196

DESIGN FOR A GARBAGE CAN STAND

Viggo Laursen, Adams County, Colo., assignor to William A. Albright, Denver, Colo.

Application September 13, 1940, Serial No. 95,011

Term of patent 3½ years

To all whom it may concern:

Be it known that I, Viggo Laursen, a citizen of the United States, residing in the county of Adams and State of Colorado, have invented a new, original, and ornamental Design for a Garbage Can Stand, of which the following is a specification, reference being had to the accompanying drawing, forming part thereof.

I claim:

The ornamental design for a garbage can stand, as shown.

VIGGO LAURSEN.
